(57) **CLAIM**

The ornamental design for an automotive monitor combined
with digital video disc player, as shown.

DESCRIPTION

FIG. 1 is a front, bottom and right side perspective view of
an automotive monitor combined with digital video disc
player, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is an enlarged cross-sectional view thereof, taken
along line 8—8 of FIG. 2, with the internal system omitted;
and,

FIG. 9 is a front, bottom and right side perspective view with
the lid opened thereof.
